PARTITION

Axel G. Dawson, Jamestown, N. Y., assignor to
 Dahlstrom Metallic Door Company, Jamestown,
 N. Y., a corporation of New York

Application February 3, 1933, Serial No. 655,047

3 Claims. (Cl. 189—34)

This invention relates to metal partitions and particularly to the details of construction and assembly thereof.

The preferred embodiment of the invention discloses the use of uprights to form the rails of a panel unit and the rough jamb of a door which, when spacedly connected and provided with suitable face plates covering the spaced connection, simulates a pilaster of conventional design for a metal partition. The invention further discloses a unital door frame which may be vertically adjusted to meet any requirements of installation.

The present trend in manufacturing metal partitions is to produce structure having few easily assembled or disassembled parts, the whole being sufficiently rigid for the work required. Public demand has resulted in applicant's development of structural means for eliminating the conventional post or pilaster between which doors and panel units were located by combining the supporting features of the post or pilaster into rails which form a part of the panel unit and the door frame structure. Such an arrangement has also been further developed to provide a vertically adjustable door frame structure by which to meet any installation requirement such as the allowance for clearance of a door over carpeting extending through the doorway.

The important objects of the invention are, therefore: (1) The provision of a vertically adjustable door frame; (2) The elimination of separate pilasters and the combination of the structural support thereof into the rails of panel units and door frames; (3) Means for producing the effect of pilasters interposed between panel units; and (4) Means for anchoring adjacent ends of units.

Other and further objects of the invention will be clearly understood from a consideration of the following specification which is taken in conjunction with the accompanying drawing, and in which

Fig. 1 shows an elevation of a partition embodying the preferred form of this invention;

Fig. 2 is an enlarged horizontal sectional view, taken substantially on the line A—A of Figure 1;

Fig. 3 is a fragmentary isometric view, showing the means for anchoring the supporting members of the partition to a floor block;

Fig. 4 is a fragmentary isometric view, parts being broken away to disclose the relationship between an adjacent panel unit and door jamb; and

Fig. 5 is a perspective view of one of the tie straps 30 by which two adjacent panel units are connected.

The invention hereinafter fully described is shown embodied in a partition, generally indi-

cated by the reference numeral 10. The partition includes panel units 11 and intermediate supporting elements 12 and 13, having the appearance of conventional pilasters or posts.

Reference is had particularly to Figure 4 of 5 the drawing in which is shown the preferred form of applicant's invention by which to eliminate the provision of intermediate posts or pilasters without sacrificing the symmetry and 10 artfulness of a partition as they have heretofore been constructed. This is accomplished through the provision of a pair of channel members 14 and 16. Each member includes a base wall 17 which is broken on the longitudinal center line thereof by a recess 18 into which is fitted a glass 15 or other panel 19. The members 14 and 16, identical in shape, are disposed with the side walls 21 and 22 directed toward each other. These walls are each formed with an inwardly opening, longitudinally extending recess 24. Adjacent the inwardly directed recesses 24 and having a common wall 25, is an outwardly opening recess 27. The opening of the recess 27 is restricted by the return bent flange 28. The flange 28 and recess 27 cooperate to receive and engage a tie strap 30. The strap 30 is formed with a base portion 31 which terminates at its vertical ends in shoulders 32. From the shoulders 32, flanges 33, directed at right angles to the base 31, are terminated by further flanges 34. 30 The flange 34 fits into the recess 27, the end of said flange being secured against removal by the return bent flange 28. It is evident that, since the metal from which the partition is made is very rigid, provision must be made for engaging 35 the flanges of the tie strap with the flanges of the channel member. This is accomplished by the provision of slots 36 which are cut into the channel member flanges 28 as well as the walls 40 of the recess 27. The tie straps being slightly tapered must, when lying in the slots 36 for the purpose of engaging the channel members, be driven into place and cannot, therefore, be inadvertently dislodged.

Secured to the channel members 14 and 16 at 45 their lower ends in any suitable manner, as by welding, are plates 37. These plates lie one within the confines of each member, being fitted with an adjusting screw 38, the purpose of which is to raise or lower the channel members with respect to the floor to overcome any floor unevenness and to cause the panel units, of which the channel member forms a part, to be properly aligned.

By reason of the fact that the channel members constitute the upright supports of the partition, it is necessary that they be anchored against any lateral movement with respect to the floor. This is accomplished through the provision of an anchor block 40 which is fastened to 55 60

the floor by means of a screw or bolt 41. In the upper face 42 of the block, slots 43 are cut for the purpose of receiving anchor brackets or plates 44. Each bracket is channel shaped, having a base wall 45 and diverging side walls 46. The side walls 46 terminate in flanges 48 which are of a size to fit the recesses 24 in the walls 21 and 22 of either of the channel members 14 or 16. The base wall 45 and small tapered portions of the side walls produce a tongue 49 which extends beyond the bracket proper. The bracket, after mounting, is moved downwardly to engage the tongue with the adjacent slot 43 in the anchor block 40 and when driven into place prevents lateral movement in any direction of the channel member.

As brought out above, the channel members 14 and 16 may constitute a part of a panel unit or a rough jamb. In the present instance (see Figures 2 and 4) the member 14 constitutes a part of the jamb and the member 16 a part of the adjacent panel unit. When these members are moved to occupy a position such that the anchor brackets 44 may be moved downwardly to register with the anchor block 40 and the tie straps 30 attached as set forth above, there is produced what may be termed a skeleton post or pilaster. To complete the simulation of a pilaster, face plates 51 are provided, the side walls of which have inturned flanges 52. These plates are snapped into place over the shoulders 32 of the tie straps 30. It may be understood that the face plates are readily removable for the purpose of dismantling the partition, altering it in any way, or introducing a wiring conduit.

The channel member 14 is fitted with a part of a vertically adjustable door jamb 54. The channel member on the other side of the door is identical with the member 14 and is fitted with the appropriate portion of the jamb 54 adjacent the hinge side of the door. A number of openings 55 are formed in the base wall of the recess 18. To the rear of this base wall is located a plate 56, the vertical edges of which project into the inwardly opening recesses 24 of the channel member 14. Adjacent the sloped walls 57 of the channel member 14, which terminate in the base wall 17, are shoulders 58. These shoulders receive the inturned flanges 60 of the side walls 61 of the jamb portion 54. One of the side walls 61 is doubled back upon itself to form a stop 62 and continues across the depth of the jamb to the other side wall 61. The jamb portion 54, being channel shaped, forms a recess 64 in which is located a channel shaped bracket 65. The edges of the side walls 67 of the bracket 65 lie against the inner face of the flanges 60 of the jamb portion 54. An opening is made in the base wall of the bracket, being aligned with the recess 18 of the channel member 14. A bolt 68 is projected through the bracket, recess 18, opening 55, and a suitable opening in the plate 56. A nut 69 is threaded on the bolt and when turned down draws the bracket 65 and plate 56 toward the shoulders 58 of the channel member 14. Since the flanges 60 of the jamb portion 54 are interposed between the shoulders 58 of the channel member and the flanges 67 of the bracket 65, the jamb 54 may be frictionally secured in any desired vertical position relative to the channel member 14.

The method of fastening the other vertical element of the jamb is identical with that above

described. The head portion 71 of the jamb is similar to the portion 54 just described with the exception that the side walls 72 thereof terminate in return flanges 73 which abut the adjacent walls 74 of the panel unit 75 above the door. The ends of the portion 71 of the jamb may be mitered or overlapped and welded or otherwise suitably joined to the vertical portions 54 to create a U-shaped jamb having vertical adjustability for the purposes intended. It is contemplated with the provision of four or five frictional securing units on each of the vertical elements of the jamb, said jamb will satisfactorily support a door of any desired weight and style.

Referring particularly to the vertically adjustable jamb structure above described, it will be noted that, when the face plates 51 are removed from engagement with the tie straps 30, access may be had to the nut 69 which, when slightly loosened, permits vertical adjustment of the jamb. It not infrequently occurs that, when a partition is set up, it is found desirable to have a door swing from the opposite side to that for which it was originally contemplated. With the present invention, it is possible to accomplish this by disengaging the wedge shaped tie straps 30 from the adjacent channel members 14 and 16, removing the anchor plates 44 from engagement with the blocks 40, lowering the entire jamb to a point where the side walls 71 of the head portion are clear of the flanges 74 of the panel unit 75 and remove the jamb as a unit. It may then be turned around, inserted from the opposite side of the partition, the tie straps interlocked with the adjacent channel members, the jamb adjusted to the desired height and frictionally locked by turning down the nuts 69, and finally replacing the face plate 51.

Although applicant has shown and described only one modification of his invention, it is not intended that he be limited thereto since it will be apparent to those skilled in the art that other modifications or adaptions of the invention may be made without departing from the spirit and scope of the hereunto annexed claims.

Having thus set forth my invention what I claim as new and for which I desire protection by Letters Patent is:

1. In partition construction, panel units, upright members defining the vertical limits of said units, flanges forming longitudinally extending pockets in the sides of each of said members, said flanges being slotted to receive tie straps for interlocking adjacent of said members in spaced relationship.

2. In partition construction, a supporting member forming part of a partition unit, flanges in said member defining longitudinally extending pockets, a bracket, flanges on said bracket engageable with said pockets, said bracket being adjustable to connect said member with an anchor block to prevent lateral displacement thereof.

3. In partition construction, a supporting member forming part of a partition unit, a bracket removably joined to and adjustable vertically of said member, an anchor block having openings in the upper face thereof, a tongue on said bracket registerable with one of said block openings whereby to secure said member against lateral displacement.

AXEL G. DAWSON.
